ATTORNEY

UNITED STATES PATENT OFFICE.

JAMES V. SCHRAIG, OF RICHMOND HILL, NEW YORK.

RECEPTACLE TERMINAL BLOCK.

Application filed December 12, 1927. Serial No. 239,605.

The main object of the invention is to provide an accessory used in the marine circuits and consists of a receptacle terminal block which is so constructed as to be simple 5 in construction, and inexpensive in cost of manufacture.

Another object of the invention is to provide a receptacle terminal block from which contact tongues project, the latter being anchored 10 by having their lower ends embedded in the block.

The above and other objects will become apparent in the description below in which characters of reference refer to like-named 15 parts in the drawing.

Referring briefly to the drawing, Figure 1 is a top plan view as mounted within a receptacle which is used generally in ships.

Figure 2 is a longitudinal cross sectional view thru the terminal block showing the method of anchoring the terminal block tongues in place.

Figure 3 is a cross sectional view thru the terminal block the section being taken on 25 line 3—3 of Figure 2.

Referring in detail to the drawing, the numerals 10 indicate the four walls of a container or receptacle which together with a bottom and removable cover (not shown) 30 provides a compartment 11 in which the blocks are positioned. These receptacles are provided with ears 12 and the parallel side walls are provided with lugs 13 thru which threaded openings pass, the openings being 35 adapted to receive the threaded ends of conduits thru which the lead wires enter the receptacle.

The terminal block is a rectangular structure which is composed of some suitable insulating material and is indicated by the 40 numeral 14. This terminal block 14 has a seat 15 which is smaller than the area of the block and has a plurality of countersunk holes 16 passing thru the center thru which screws pass when anchoring the terminal blocks in the receptacle. A channel passes 45 thru the center of the block and on both

sides of this channel tongues 17 and 18 are positioned. The tongues consist of two joined areas of material which are parallel to each other and are constructed in this fashion to give resiliency to the tongues. The lower ends of the tongues are provided with right angle extensions 19 which are embedded in the block. These extensions 50 are positioned so that they lie in contact with bridge plates 20 which are also embedded intermediate their length in the terminal block as is indicated in the sectional view indicated in Figure 3. The ends of 55 the plates 20 are fashioned into ears 21 which are raised above the central portion of the bridge plates. The ears 21 are provided with openings having screws 22. The latter engage threaded openings in the block 60 and are adapted to have the ends of lead wires wrapped about them and be secured by 65 the screws.

The receptacles into which the terminal blocks are placed are of standard size and 70 with the type of block previously used short circuit thru corrosion often occurred. With this type of terminal block this element of danger is removed by the construction of the blocks.

I claim:

1. A terminal block comprising a rectangular base element, said block being composed of insulating material, tongues having their lower ends embedded in said block, 80 and bridge plates partly embedded in said base and lying in contact with said tongues.

2. A terminal block comprising a rectangular base element, tongues projecting from said block, rightangled extensions on said tongues embedded in said block, longitudinal bridge plates lying embedded in said block and having ears in contact with the extensions of said tongues, and screws mounted in the ends of said bridge plates. 90

In testimony whereof I affix my signature.

JAMES V. SCHRAIG.
